(57) **CLAIM**

The ornamental design for a torque application tool, as shown and described.

DESCRIPTION

FIG. 1 is a side perspective view of an embodiment of a torque application tool;

FIG. 2 is a first side view of the embodiment in FIG. 1;

FIG. 3 is a second side view of the embodiment in FIG. 1;

FIG. 4 is a third side view of the embodiment in FIG. 1;

FIG. 5 is a fourth side view of the embodiment in FIG. 1;

FIG. 6 is a first end view of the embodiment in FIG. 1; and,

FIG. 7 is a second end view of the embodiment in FIG. 1.

Any components in the drawings shown in broken lines are for illustrative purposes only and form no part of the claimed design.
